UNITED STATES PATENT OFFICE.

BLANCHE G. OSBORNE, OF CORNING, IOWA.

TYPEWRITER PAD.

1,417,556.

Specification of Letters Patent. Patented May 30, 1922.

Application filed September 20, 1919. Serial No. 325,115.

To all whom it may concern:

Be it known that I, BLANCHE G. OSBORNE, a citizen of the United States, residing at Corning, in the county of Adams 5 and State of Iowa, have invented certain new and useful Improvements in Type-writer Pads, of which the following is a specification.

This invention relates to typewriter pads. 10 The object of the invention is to provide a pad constructed to eliminate the use of ribbons and which is so constructed as to properly retain the ink thereby greatly prolonging the life thereof rendering it both 15 practical and economical.

Another object is to provide a pad of this character which may be readily slipped on or off the ribbon vibrator, as for instance in the Remington typewriter machines.

20 Another object is to so construct a pad of this character that the type will be prevented from clogging thereby avoiding the necessity of cleaning them except occasionally.

25 With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

35 In the accompanying drawings:—

Figure 1 represents a front elevation of a typewriter pad constructed in accordance with this invention and shown applied, the 40 support therefor being shown broken off,

Fig. 2 is a top plan view thereof,

Fig. 3 is a transverse section taken on the line 3—3 of Fig. 1,

Fig. 4 is a front elevation of the pad detached, and

Fig. 5 is a detail longitudinal section on an enlarged scale taken on the line 5—5 of Fig. 4.

In the embodiment illustrated, the pad 50 1 constituting this invention is equipped with tubular supports 2 at its opposite ends which are split longitudinally and provided along the walls of said split with outwardly projecting lips 3 which are preferably corrugated to clampingly engage the ends of the pad which is secured thereto by rivets

or other fastening elements 3^a as is shown clearly in Fig. 4, the ends of the pad being extended into the tubes 2 as is shown clearly in Fig. 5.

The pad numbered 4 is composed of two separate layers 5 and 6, one of which is constructed of fine grade canton flannel having a firm nap and a fine smooth back and which is here numbered 6. The other layer 5 is composed of the same quality silk as that which is used in making typewriter ribbons but it is inked somewhat heavier. The edges of the two strips 5 and 6 are selvedged. The ends of the strips 5 and 6 after entering the tubes 2 diverge as shown in Fig. 5 and are secured by the rivets 3^a as above described.

In the use of this pad, the tubular members 2 are engaged by the upright supporting pins 7 which are carried by the ribbon vibrator. These pins 7 are here shown having hook-shaped ends which enter the tubes 2 and they are fixed in arms 8 of the vibrator 9. The ribbon vibrator 9 and guide 10 which are of usual construction, are also employed for holding the pad in operative position and between which the type is designed to operate, the pad being shaped in exactly the same manner as is the ribbon. In the use of this pad, the silk side 6 is disposed next to the paper and the keys come in contact with the cotton inking layer 5. This pad may be reinked with the same ink which is used by manufacturers in inking ribbons and when found necessary may be removed and another substituted.

By so constructing the pad, the life thereof is greatly prolonged and the type are prevented from being clogged, thus dispensing with the work which usually falls to the typist of cleaning such type, and the replacing of new ribbons, is also dispensed with, which is very laborious as well as dirty.

From the foregoing description, taken in connection with the accompanying drawings, the advantages of the construction and of the method of operation will be readily apparent to those skilled in the art to which the invention appertains and while I have 100 described the principle of operation of the invention together with the device which I now consider to be the best embodiment thereof, I desire to have it understood that the device shown is merely illustrative and 105 that such changes may be made as are within the scope of the claimed invention.

Having thus fully described my invention, what I claim as new and desire to secure by Letters Patent, is:—

A typewriter pad comprising inked fabric, tubular supports engaging the opposite ends thereof, said supports being split longitudinally and provided with radially extending clamping lips to receive the ends

of the pad and to connect them to the ribbon vibrator of a typewriter.

In testimony whereof I affix my signature in presence of two witnesses.

BLANCHE G. OSBORNE.
